UNITED STATES PATENT OFFICE

LAWRENCE THOMAS WARD, OF KANE, PENNSYLVANIA, ASSIGNOR TO KANE MANUFACTURING COMPANY, OF KANE, PENNSYLVANIA, A CORPORATION OF PENNSYLVANIA

SKYLIGHT BLIND

Application filed November 29, 1930. Serial No. 499,110.

This invention relates to skylight blinds and has particular reference to a blind construction wherein the parts thereof, including supporting members, are arranged to be erected and operated in a horizontal position within the opening below a skylight.

The principal object of my invention is to provide a supporting frame for a plurality of pivotally mounted slats wherein the main elements of the frame may be readily assembled and supported within a skylight opening.

Another object is to provide a plurality of slats and pivotal supports therefor that may easily be mounted upon a supporting frame and which may be placed in position from below the frame.

Another object is to provide a plurality of slats which are arranged within a horizontally positioned frame so as to be operable with a minimum of effort and which will remain in any desired tilted position.

Another object is to provide a plurality of slats arranged in a horizontal plane and manually operable means therefor that may be controlled from a remote position below the slats.

A further object is to provide a skylight blind that is simple in construction, easy to install and operate, as well as economical to manufacture.

Other objects will appear from the detailed description which follows.

In the accompanying drawings,—

Figure 1 is a view in perspective partly in section, showing a skylight and blind constructed according to my invention;

Fig. 2 is a sectional view on line 2—2 of Fig. 3;

Fig. 3 is a plan view of a blind with the slats in open position;

Fig. 4 is a sectional view on line 4—4 of Fig. 3; and

Fig. 5 is a view showing details.

Referring to the drawings in detail, where-

in similar numerals indicate corresponding parts, a conventional form of skylight 1 is shown mounted in position upon and above the usual light well 2 and is provided with the usual glass panes 3. My improved blind includes, in combination, as an important feature a frame or slat support 4 so constructed that it may be shipped from the factory in a knockdown form. The frame 4 comprises a pair of side members 5 and a pair of end supports 6. Each side member 5 is provided with an integral lateral extension 7 which not only provides an extended surface 8 in contact with the end supports 6, but also serves to receive the screws 9 which fix the members 5 in position on the end supports 6.

A plurality of slat pivot bearings 10 are mounted in openings 11 formed in each side member 5. A slat holder in the form of a steel stamping 12 is pivotally mounted in each bearing 10 by means of a slat pivot 13. A plurality of slats 13' are mounted upon the holders, one slat for each opposite pair of holders. In order to provide a detachable mounting for each slat, I form a slot 14 in each slat and an opening 15 in each side of the holder 12. After the slat end is positioned between the side walls of the holder, a cotter pin 16 is passed through the opening 15 and slot 14. Such construction provides a simple and economical means of detachably mounting the slats whereby the latter may be placed in position after the frame 4 is assembled. All parts may be assembled by a workman positioned below the frame 4.

A rocker bar 17 is pivotally mounted by means of pins 18 at one side of the frame 4 upon a series of upwardly extending lugs 19 formed upon the holders 12 located at that side of the frame. A slat operating pulley 20 is rotatably mounted on an axle 21 supported in one of the side members 5. The pulley may be mounted on either side member in any desired position thereon.

A pair of fixed end slats 22 are supported within slots 23 formed in the side members 5 and each end slat is engaged at its outer edge by a reinforcing guide support 24. The bar 17 is pivotally connected to a link 25 which extends laterally from the pulley 20. A pulley operating cord 26 engages the pulley and extends to a position below the blind. The cord is retained by a clamp 26' supported 10 on the link 25.

A flexible finish strip 27 is attached along the upper edges of the frame members 5 and may be bent to contact any irregular contour of the walls of the light well 2, thereby to 15 exclude light at that point.

A filler strip 28 may be provided, as shown in Fig. 1, on the member 5 which supports pulley 20 and the strip 28 is interrupted adjacent the pulley to provide a pulley recess. 20

In assembling the various parts in position within a skylight well, the end supports 6 are first mounted at the desired position therein. The side members 5 assembled with the slats 22 and guides 24 are then fastened to 25 these supports by means of the screws 9, and strips 27 are nailed in the proper position on the members 5. The holders 12 are then mounted on their respective bearings 10 and the rocker bar 17 is connected to the pulley 30 20 by the link 25. Finally, the slats 13' are inserted between the side walls of the holders 12 and are fastened thereto by pins 16.

It will be noted that each slat is mounted 35 on pivots positioned on the center line of the slat. The points of attachment of the ends of the link 25 are equidistant from the center of the pulley 20. This relation of moving parts permits an operation of the slats with a minimum of effort and the slats will remain 40 in stable equilibrium in any adjusted position.

It will be readily perceived that a blind 45 constructed according to my invention possesses novel features in combination which are particularly adapted for use in skylight installations. Its construction and operation secures advantages and results which are new and desirable in the application described. The various parts are simple in construction, easy to assemble and efficient in 50 operation.

While I have shown and described a preferred form of my invention, it is to be understood that various modifications there- 55 of are contemplated within the scope of the appended claims.

What I claim is:

1. In a skylight blind, a frame comprising 60 end supports and side members, said end supports being arranged to support said side members in a horizontal position within a skylight well, means for detachably mounting said side members on said end supports, and a plurality of slats pivotally mounted on 65 said frame.

2. In a skylight blind, a frame comprising end supports and side members, said end supports being arranged to support said side members in a horizontal position within a skylight well, inwardly extending portions 70 adjacent the lower edges of said side members in position to contact with end supports, fastening means extending through said extending portions and into said end supports, and a plurality of slats pivotally mounted on 75 said frame.

3. In a skylight blind, a frame comprising end supports and side members, said side members being provided with a plurality of 80 openings, a slat support pivotally mounted in each of said openings, a plurality of slats, each slat being provided with an opening adjacent each end thereof, each slat support being provided with an opening, said slats engaging said slat supports, and detachable 85 fastening means extending through adjacent support and slat openings.

4. In a skylight blind, a frame, a plurality of slat holders pivotally mounted on said frame, a plurality of slats, means for detachably mounting said slats on said slat holders, a rocker bar pivotally associated with said slat holders adjacent common ends of said slats, an operating pulley, means connected to said bar and to a point adjacent 95 the periphery of said pulley, and means for rotating said pulley.

5. In a skylight blind, a frame comprising side members, each side member being provided with a slot adjacent each end thereof, 100 end slats slidably engaging said slots, a plurality of slats pivotally mounted on said frame, said end slats being mounted in position to engage the endmost pivoted slats when the latter are rotated to extreme positions. 105

6. In a skylight blind, a frame, means for mounting said frame in horizontal position within a skylight well, a plurality of slats pivotally mounted on said frame, a rocker bar pivotally mounted on said slats, a pulley mounted on said frame, a link pivotally connected to said bar and to a point adjacent the periphery of said pulley, and an operating cord engaging said pulley and extending below said frame. 115

7. In a skylight blind, a frame comprising end members and a pair of side members, a plurality of slats pivotally mounted on said side members, a rocker bar pivotally mounted on said slats, means providing a recess in one of said side members, a pulley positioned in said recess and connected to said bar, and an operating cord associated with said pulley. 120

8. In a skylight blind, a frame comprising 125 opposite side members, each of said members being provided with a plurality of openings, a plurality of slat supports, each support comprising an integral laterally extending pivot pin and a slat engaging flange, each 13

5 pivot pin extending within a related opening when in assembled position, and a slat member detachably engaging the flange of each slat support, whereby the pivot pins of said supports may be removed from the related opening together with the integral flange as a unit after the slat is detached from the flange.

In testimony whereof I affix my signature.
